UNITED STATES PATENT OFFICE.

JAMES FATKIN, OF GULCH, COLORADO.

WRENCH.

SPECIFICATION forming part of Letters Patent No. 663,161, dated December 4, 1900.

Application filed April 25, 1900. Serial No. 14,242. (No model.)

To all whom it may concern:

Be it known that I, JAMES FATKIN, a citizen of the United States, residing at Gulch, in the county of Pitkin and State of Colorado, have 5 invented certain new and useful Improvements in Wrenches; and I do hereby declare the following to be a full, clear, and exact description of the invention, such as will enable others skilled in the art to which it appertains to make and use the same.

This invention relates to certain new and useful improvements in wrenches for pipes, rods, tubes, nuts, and the like.

In the accompanying drawings, Figure 1 is 15 an edge view of a wrench embodying my invention. Fig. 2 is a side elevation thereof with a portion of the handle broken away and shows in dotted lines a pipe or tube in position to be grasped by the jaws. Fig. 3 is 20 a view similar to Fig. 2, showing the jaws closed upon the pipe or tube. Fig. 4 is a central vertical section on the line 4 4 of Fig. 5, a portion only of the handle being shown in elevation. Fig. 5 is a section on line 5 5 of 25 Fig. 4. Fig. 6 shows in side elevation a slightly-modified form of the wrench, part of the handle being omitted. Fig. 7 shows in side elevation and partial section a slightly-modified form of wrench. Fig. 8 is a rear 30 end view of the sliding jaw with the screw and its connected parts removed. Fig. 9 is a side elevation of the parts shown in Fig. 8, with a portion of the movable jaw broken away. Figs. 10, 11, and 12 are side and end 35 elevations and bottom plan view, respectively, of the nut. Fig. 13 represents in side elevation and bottom plan view a modified form of nut. Fig. 14 is a sectional view similar to Fig. 5, showing a slight modification in 40 the location of the pivot upon which the nut swings.

Similar letters of reference indicate similar parts throughout the several views.

In the drawings, A represents the handle 45 of the wrench, which may be of a size and shape adapted to the particular use for which it is intended. At its end the handle carries a stationary jaw A', preferably formed with a serrated or notched face a, at a suitable pre- 50 determined angle to the handle A, as shown. Rising from each side of the handle and preferably above the jaw A' are the two cheek-

pieces a' a', between which the movable jaw B is adapted to have a sliding movement, as will hereinafter appear. The movable jaw 55 B, which projects beyond the stationary jaw, is preferably provided at its front end with a serrated face b, which in the operation of the wrench is adapted to coact with the serrated face a of the fixed jaw, and extending rearwardly from said front end the said jaw B has a body portion B', which is adapted to fit and slide between the cheek-pieces a' a' and is provided with a longitudinal slot b'. Carried by said body portion of the sliding jaw, 60 65 and preferably seated in a groove formed therein below the slot b', is a screw B², the forward end b² of which is seated in a socket in the jaw and the plain or unthreaded rear end b⁴ of which passes through a bearing b⁵ in the 70 rear of the body portion and beyond said bearing is provided with a fixed collar b⁶. (See Fig. 4.) The extreme rear end of the body portion of the sliding jaw is preferably extended, as at b⁷, Fig. 4, and is provided 75 with an external screw-thread upon which a correspondingly internally threaded ferrule b⁸ is fitted in a manner to prevent relative endwise movement between the screw B² and the sliding jaw and to receive end thrust of 80 the screw.

In order to provide a ready means for manipulating the screw B² by turning it in the sliding jaw as desired, the screw is extended through and beyond the ferrule b⁸, as at b⁹, and 85 has fixed thereto, preferably by a pin or set-screw b¹⁰, a knurled head b¹¹. Thus the ferrule b⁸ and collar b⁶ prevent the screw from moving endwise in the sliding jaw, although permitting it to be readily turned or rotated 90 therein.

Seated in the longitudinal slot of the sliding jaw is a nut C, provided, preferably on its under surface, with a screw-threaded groove c, adapted to engage the threads of the screw 95 B². This nut fits between the cheek-pieces a' a', in which it is loosely connected by a pivot-pin c', which passes through a hole c² in the nut above the screw-threads c. The nut C is provided with projections c³, which extend beyond 100 the sides of the body portion of the movable jaw and embrace the cheek-pieces a' a'.

In assembling the parts the nut C is placed in the slot of the movable jaw, the screw is

inserted, the ferrule or thimble is screwed into the end of the movable jaw, the knurled or milled head is placed on the end of the screw and fastened by the pin or rivet b^{10} , and the sliding jaw, screw, and nut are then placed between the cheek-pieces of the stationary jaw or head, and the pivot-pin or rivet c' is passed through the cheek-pieces and nut and headed, so as to hold the parts from dis-
10 placement.

From the construction described and shown it will be evident that by manipulating the screw B^2 by means of the knurled head b^{11} the movable jaw B may be moved back and forth with relation to the fixed jaw A' to thereby adjust said jaws to grasp a pipe, rod, or tube, as at P , Fig. 3, whereupon by turning the handle A in the direction of the arrow s , Fig. 3, the movable jaw will rotate upon the pin c' , thus clamping the pipe, tube, or rod with a firm grip between the faces a and b of the jaws. A reverse movement of the handle A in the direction of the arrow s' will reverse the rotation of the movable jaw, thus separating the jaws and promptly releasing the grip. As the handle is turned to grip the pipe, tube, or rod between the jaws strain will be placed upon the movable jaw, which through the screw B^2 will be transmitted to the nut C , and from it the strain will be transmitted to the cheek-pieces $a' a'$ through the projections c^3 , which relieve the pivot-pin c' .

In order to provide for the proper range of swinging movement of the movable jaw on the pivot-pin c' , and thereby secure greater efficiency in the gripping action of the jaws, the front end of the handle adjacent the stationary jaw A' is cut away or beveled, as at d , although this may not always be necessary and will depend upon the height of the pin connection between the cheek-pieces and the degree of swinging movement desired for the sliding jaw.

While I have described the above as the preferred embodiment of my invention, yet the construction is susceptible of modifications and changes—as, for instance, instead of placing the screw B^2 in a recess in the body portion of the movable jaw such recess might obviously be dispensed with, or, as illustrated in Fig. 6, the screw might be placed above the slot b' and nut C . In this latter construction it is preferable, though not necessary, to provide a recess or groove in the upper face of the slot b' for the reception of the screw B^2 , and of course the nut C instead of having a screw-threaded groove on its under face would be provided in such case with a groove on its upper face, and the pin c' will loosely connect the nut to the cheek-pieces below rather than above the central axial line of the nut, as in the preferred construction. In all other respects, however, the parts of the wrench illustrated in Fig. 6 are the same as those previously referred to and need no further description herein.

Since the strain to which the movable jaw

is subjected is always lengthwise of the wrench, with a tendency to force the sliding jaw longitudinally away from the stationary jaw, it is not necessary that the nut C should have lugs or projections $c^3 c^3$ at both ends thereof. In fact, as illustrated in Fig. 13, the lugs at one end of the nut C' may be omitted altogether, in which case the lugs on the opposite end of the nut would be placed so as to engage the cheek-pieces on the sides thereof opposite the face b of the movable jaw in such manner that any strain tending to force the sliding jaw longitudinally away from the stationary jaw would be communicated to the cheek-pieces through the lugs or projections on the nut, thus relieving the strain on the pin c' .

While the manner of connecting the screw B^2 to the sliding jaw has been described in its preferred form, as illustrated in Fig. 4, yet it is evident that the details thereof may be varied in many respects. For instance, instead of extending the rear end of the sliding jaw to form the screw-threaded bearing b^7 for the ferrule b^8 the said extension may be omitted and the rear end of the sliding jaw be internally screw-threaded, as at b^{17} , to receive the exteriorly-threaded ferrule b^{18} , as in Fig. 7.

By pivoting the sliding jaw to the cheek-pieces loosely and providing the nut with projections to engage the cheek-pieces the pivot-pin c' may be made light and yet durable, as all strain on the sliding jaw is transmitted through the heavier projections bearing against the cheek-pieces, and, if preferred, the pivot-pin may be located in the center of the cheek-pieces, as shown in Fig. 14, instead of in the upper part of the nut, as shown in Fig. 4, or in the lower part of the nut under the screw, as shown in Fig. 6; but in this case the pivot will consist of short studs projecting into recesses in the nut instead of passing clear through the nut, as in the other constructions.

What I claim is—

1. A wrench, comprising an operating-handle provided with a fixed jaw, cheek-pieces projecting from said handle, a slotted movable jaw adapted to slide between the cheek-pieces, a nut adapted to rock upon a center between the cheek-pieces and having projecting portions adapted to engage the outer edges of the cheek-pieces to sustain the thrust upon the movable jaw, and a screw carried by the movable jaw and engaging said nut; substantially as described.

2. A wrench, comprising an operating-handle provided with a fixed jaw, cheek-pieces projecting from said handle on each side of said jaw, a movable jaw provided with a slotted body portion, a nut in said slotted body portion and provided with a threaded groove, said nut being loosely pivoted between the cheek-pieces and having projections to engage the edges of the latter, the said slotted body portion of the movable jaw being provided with a longitudinal groove, and a screw

seated partially in said groove and engaging the threaded groove of the nut, substantially as described.

3. A wrench, comprising an operating-handle provided with a fixed jaw, cheek-pieces projecting from said handle on each side of the jaw, a movable jaw provided with a slot, a nut in said slot, a screw carried by the movable jaw and provided with a collar, and a ferrule bearing against said collar to retain

the screw in proper position in the movable jaw and receive the thrust of the screw, substantially as described.

In testimony whereof I affix my signature in presence of two witnesses.

JAMES FATKIN.
